MATTHEW CLINTON, OF NEW YORK, N. Y.

Letters Patent No. 98,229, dated December 28, 1869.

IMPROVED SELF-ADJUSTING CART-SADDLE.

The Schedule referred to in these Letters Patent and making part of the same

To all whom it may concern:

Be it known that I, MATTHEW CLINTON, of the city, county, and State of New York, have invented a new and improved Self-Adjusting Cart-Saddle; and I do hereby declare that the following is a full, clear, and exact description of the same, reference being had to the accompanying drawings, and to the letters of reference marked thereon, making a part of this specification.

This invention relates to a new and improved harness-saddle, of that class which is designed to support the shafts or thills of a two-wheel vehicle, such as a cart, gig, &c., and is constructed so as to have a good bearing-surface on the back of the animal.

The invention consists in a novel construction of the saddle, as hereinafter fully shown and described, whereby the same is rendered self-adjusting, and made to conform to the movement of the animal, and at all times adjust itself properly to the shape of the back of the animal.

In the accompanying sheet of drawings—

Figure 1 is a plan or top view of my invention.

Figure 2 is a rear view, and

Figure 3, an inverted plan of the same.

Similar letters of reference indicate corresponding parts in the several figures.

To enable those skilled in the art to fully understand and construct my invention, I will proceed to describe it.

A A represent two blocks, which may be of wood, and of a size corresponding to pads B B, for the back of the draught-animal to which the saddle is to be applied, the pads being attached to the blocks by loops, strings, or other suitable means.

These blocks A are covered by plates C, which may be of sheet-metal, japanned, if desired, or polished bright, said plates being screwed or tacked to the blocks, and projecting a little beyond the same all around.

The two blocks A A are connected by a curved flat metallic bar, D, the curvature forming a part of a circle, as shown in fig. 2, and having a loop, or ring, a, at each end, to which the belly-band is attached.

The bar D is attached to the blocks A A by pivot-bolts b, which pass down loosely through holes in D, and through the centres of metallic plates E E, which rest or bear on the cover C of the blocks, the plates being concave at their under sides, so that their ends will bear on the covers C, the bar D resting or bearing on the central prominent parts of E E, as shown clearly in fig. 2.

The bolts b also pass through the blocks A A, and may have a screw-nut and washer on their lower ends, or have a washer and head below the latter, the upper ends of the bolts being headed, to retain the bar D, but not to prevent or interfere in the least with the free working or movement of the pad-blocks A.

By this arrangement a sort of universal joint is

obtained, which will allow of each block and pad working freely, to conform to the motion of the animal, and also admit of the two parts of the saddle conforming to the shape of the back of the animal.

Besides this bar D, the two parts or blocks A A, with their attached pads, are connected by a bar, F, the ends of which are secured to the blocks by pivot-bolts d d, which pass loosely through the bar F, and have heads on their upper ends.

This bar F preserves the parallelism of the two parts of the saddle, retaining them always in a proper relative position, one with the other, so that the saddle may be put on and taken off from the back of the animal with the greatest facility, equally so as an ordinary harness-saddle.

G represents the turrent-rings, through which the reins pass;

H is the crupper-strap; and

I, the check-rein hook, the latter being attached to, or formed on the front end of a bar, J, which is pivoted to the bar D, and the former fitted in a loop, or ring, e, at the rear end of J.

K is a metal rod, which is curved, to correspond with the curvature of the bar D, and is fitted loosely in guides, f, attached to said bar.

The rod K is allowed to slide, or work freely, in the guides f, and at each end it is bent to form a hook, g, to receive the chains or straps which hold up the shafts or thills of the vehicle.

The pads B B may be stuffed with curled hair, or other suitable material. Hair would probably be the preferable material.

From the above description it will be seen that the two parts of the saddle will be allowed to work or move freely, forward or backward, and upward or downward, and thereby conform to the motion or movement of the animal, and, at the same time, adjust itself to the shape of the back of the animal. The latter, therefore, will not be fatigued, jaded, or annoyed in any way under the pressure or weight of the saddle, nor liable to be chafed or galled by any friction of the same.

The invention also possesses the advantage of economy, as they may be constructed at a less cost than the ordinary cart-saddles in use, and may be repaired, when they require it, at a very moderate expense.

Having thus described my invention,

What I claim as new, and desire to secure by Letters Patent, is—

The padded blocks A A, connected by the curved bars D F, in connection with the curved rod K, fitted on bar D, all constructed and arranged substantially as and for the purpose set forth.

MAT. CLINTON.
